UNITED STATES PATENT OFFICE.

GEORGE S. KEBABIAN, OF NEW YORK, N. Y.

MACHINE FOR TREATING AND REFINISHING RUGS AND TEXTILE FABRICS.

1,093,433.

Specification of Letters Patent. Patented Apr. 14, 1914.

Application filed September 13, 1912. Serial No. 720,135.

To all whom it may concern:

Be it known that I, GEORGE S. KEBABIAN, a citizen of the United States, residing in the city, county, and State of New York, have made a certain new and useful Invention in Machines for Treating and Refinishing Rugs and Textile Fabrics, of which the following is a specification.

This invention relates to machines for treating and refinishing rugs. The term rug is used throughout the specification generically to designate all textile floor coverings, with or without nap, handmade and machine made.

The art of treating, renovating and refinishing rugs has come into being owing to the diminution in the supply of oriental rugs having the subdued tone and luster of the antique Persian rug. The problem of this art is to refinish the modern rug in such a way as to impart to it the decorative and esthetic features of the antique Persian rug. At present, the rug is first cleaned of dust and dirt. After the rug is cleaned, the refinishing process consists substantially of stripping the colors, or rather the unstable dyes of the nap of the rug, then forcing the liquid out of the rug, then drying the rug in a drying room, then ironing the rug, and sometimes, in the case of a certain class of rugs, redyeing the rug as a whole or touching up certain parts of the rug with fast dyes to produce desired shades of color. For these various steps in refinishing the rug, or a number of rugs at the same time, a number of separate devices and appliances are now in use, more or less of a primitive nature, poorly adapted for the accomplishment of proper results, inefficient and uneconomical.

One of the principal objects of my invention is to provide a machine which can be utilized for any and all of the processes necessary for the treatment and refinishing of rugs in an efficient, expeditious and economical manner, adapted to produce the results sought after in the art.

Other objects of my invention will appear more fully hereinafter.

The invention consists substantially in the construction, location, and relative arrangement of parts, all as will be more fully hereinafter set forth, as shown in the accompanying drawings, and finally pointed out in the appended claim.

Referring to the accompanying drawings

and to the various views and reference signs appearing thereon: Figure 1, is a longitudinal front view, parts broken off, of a machine embodying the principles of my invention. Fig. 2, is a view in vertical transverse section looking in the direction of the arrows along the line 2, 2, Fig. 1. Fig. 3, is a detail view of the roller shifting device. Fig. 4, is another detail view showing a brush roller in place of roller A. Fig. 5, is a horizontal transverse view of the same device. Fig. 6, is a horizontal plan view, looking in the direction of the arrows, along line 6, 6, Fig. 3, of the same device. Fig. 7, is a view in vertical section, looking in the direction of the arrows, along the line 7, 7, Fig. 6, of the same device. Fig. 8, is a detail view of one of the links of the chain.

The same part is designated by the same reference sign wherever it occurs throughout the several views.

In carrying out my invention I propose to employ a tank or vat 1, made of wood, porcelain or other suitable material, and having drainage faucets 2. In the interior of the tank sprockets 5, 5' and their shafts 4, 4', are supported by a frame 3, made of any suitable or convenient material. The upper sprockets 10, 10' and their shaft 8, 8', are hung from the ceiling in any convenient way, such as by a casting 11. Two endless chains 9, 9, pass around their respective series of sprocket wheels 5, 5', 10, 10', situated at opposite sides of the tank. The uppermost shafts 8, are incased in wood D, of a sufficient diameter to permit the rugs to roll over them easily. The chain can be operated by any convenient or desired driving mechanism, such as an electric motor, by belting through pulley 7, the forward shaft of the series of shafts 8, and by driving wheels 10, carried by the shaft. Pulley 7 may be a speed cone. The links of chains 9, at intervals of say two feet have webs 12 integral therewith; rods or cleats 14 are fastened by suitable means to the webs. The rods are rounded in cross section (Fig. 2.)

Referring to Figs. 3, 4, 5, 6 roller A is carried by shaft 20. A lever 16 shifts sprocket wheel 15, also carried by shaft 20, into and out of engagement with the endless chains. Springs 17 and 18 furnish the yielding pressure for wringing out the liquid, between rollers A and B, or B and C when roller A is replaced by brush roller C.

The operation of the machine is as fol-

lows: The rugs 19, are tied or fastened in any suitable manner to the cleats 14, until the front face or plane is filled. The chains are then slowly set in motion and the rugs 5 pass over the uppermost shaft and a new surface of cleats presents itself. This operation is repeated until the total surface formed by the chains and cleats or so much of such surface as may be necessary, is covered with rugs. The rugs may then be 10 cleaned. Then by filling the tank with a suitable solution and setting the mechanism in motion any stain or dirt may be removed by washing. This solution may then be 15 drained out of the tank and another liquid, such as a solution of potassium hypochlorite (KClO) suitable for stripping or attacking the unstable dyes of the rugs, let in. The mechanism is again set in motion, and the 20 rugs are carried up and down passing in and out of the solution in the tank at frequent intervals of time. This frequent immersion and emergence adds mechanical force to the chemical force of the solution, tends to subject 25 all parts of a rug to a uniform application of the attacking liquid, and by constantly agitating the solution, prevents the formation of sediments. The frequent emergence of the rugs also presents to the operator a ready means of frequent observation 30 of the effects produced, and enables him to readily regulate the strength or temperature of the solution and to cease operation when necessary. It will also enable him 35 to detect discoloration due to the mixture of the stripped dyes with the attacking solution, in which event it will be necessary to supply a fresh solution. At the conclusion 40 of this treatment the chemical solution is drained off. The fibers of the rugs then require a cleansing from chemical matter 45 loosely adhering to them. While the rugs are in motion they can be cleaned by filling the tank with fresh water. This cleansing would be facilitated by directing a stream of 50 water down the plane of the rugs, the application of the stream being at a convenient point above the first plane. The water is then drained from the tank and roller A is shifted into position by means of lever 55 16. The rollers are held yieldingly in their

coöperative relation by springs; this fact permits the cleats and rugs of varying thickness to pass between them. A rapid motion applied to the rugs will also aid in expelling the water. To hasten the drying process a draft of air, of a temperature calculated to accelerate evaporation can also be applied at any suitable or convenient point. The final process applied to the rugs is the brush, 60 stationary, rotatory, flat or circular, as may be desired, which will remove the fine particles loosely adhering to the fibers of the nap as well as brushing or smoothing the nap into place; this is necessary in order to 65 obtain a smooth and glossy surface.

Various other changes in the mechanism or mode of operation could be made and still fall within the scope of my invention and I do not desire to be limited to the 70 specific features and form of mechanism here shown.

Having now set forth the object and nature of my invention and various modes of application thereof, what I claim as new 75 and useful and of my own invention and desire to secure by Letters Patent is:

In a machine for treating rugs, the combination with a tank, of frames or castings anchored in the tank for supporting horizontal shafts, frames or castings hung above and parallel to the said frames or castings, horizontal shafts supported by the frames or castings, sprocket wheels carried by the shafts, two endless chains, opposite to each 80 other, trained over the said sprocket wheels; webs on links of said chains for carrying cleats, cleats horizontally fastened on said webs for supporting and carrying rugs; driving mechanism whereby said shafts, 85 sprocket wheels and chains are rotated and revolved and whereby the chains are caused to pass in and out of said tank and means for wringing and smoothing the rugs.

In testimony whereof I have hereunto 90 affixed my hand and seal this 12th day of September 1912.

GEORGE S. KEBABIAN. [L.S.]
